US00D995936S

(12) **United States Design Patent** (10) **Patent No.:** **US D995,936 S**
(45) **Date of Patent:** **** Aug. 15, 2023**

(54) **PET WATER DISPENSER**

(71) Applicant: **Hangzhou Yijing Technology Co., Ltd.**, Hangzhou (CN)

(72) Inventors: **Dapeng Sun**, Hangzhou (CN); **Xin Chao**, Hangzhou (CN)

(73) Assignee: **Hangzhou Yijing Technology Co., Ltd.**, Hangzhou (CN)

(**) Term: **15 Years**

(21) Appl. No.: **29/893,916**

(22) Filed: **Jun. 5, 2023**

(51) LOC (14) Cl. **30-03**

(52) U.S. Cl.

USPC **D30/132**

(58) **Field of Classification Search**

Primary Examiner — Susan Moon Lee

CLAIM

The ornamental design for a pet water dispenser, as shown and described.

DESCRIPTION

FIG. 1 is a front perspective view of a pet water dispenser, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the pet water dispenser, which form no part of the claimed design.

1 Claim, 8 Drawing Sheets
